(57) **CLAIM**

The ornamental design for an electric teaser fishing reel, as shown and described.

DESCRIPTION

FIG. 1 shows a bottom plan view of the teaser reel embodying by design;

FIG. 2 illustrates a front end view thereof, the rear end view being a mirror image thereof;

FIG. 3 illustrates a left side elevational view thereof;

FIG. 4 illustrates a right side elevational view thereof;

FIG. 5 is a top plan view thereof;

FIG. 6 is a bottom, left side, front end perspective view thereof;

FIG. 7 is a second embodiment of my design showing a bottom plan view thereof;

FIG. 8 is a front end view of the design shown in FIG. 7, the rear end view being a mirror image thereof;

FIG. 9 is a left side elevational view thereof;

FIG. 10 is a right side elevational view thereof;

FIG. 11 is a top plan view thereof; and,

FIG. 12 is a bottom, left side, front end perspective view thereof.
